Attorney

UNITED STATES PATENT OFFICE.

MARY M. GELLENBECK, OF TACOMA, WASHINGTON.

GARMENT.

1,331,754.

Specification of Letters Patent. Patented Feb. 24, 1920.

Application filed March 31, 1919. Serial No. 286,440.

To all whom it may concern:

Be it known that I, MARY M. GELLENBECK, a citizen of the United States, and resident of Tacoma, county of Pierce, and

5 State of Washington, have invented certain new and useful Improvements in Garments, of which the following is a specification.

This invention relates to new and useful improvements in garment construction, and 10 the object of this improvement is to provide means for reinforcing the seam of the garment under the arm to overcome ripping and tearing thereof, and to preclude the fabric of the outer portion of the garment 15 from being worn out by the stays of the corset as formerly.

The invention consists in the arrangement 20 construction and combination of parts as will be more fully described in the following specification illustrated in the accompanying drawings and finally pointed out in the appended claims.

In the drawings,

Figure 1 is a front view of a garment 25 embodying the present invention; a part of the waist portion being broken away to illustrate the relation of the reinforcing member to the sleeve and side of the garment.

Fig. 2 is a view in vertical section of the 30 same.

Fig. 3 is an enlarged cross section of the reinforced seam.

Fig. 4 is a plan view of reinforcing sleeve.

Referring more particularly to the drawings in which like reference numerals indicate like parts, the numeral 1 designates the 35 upper portion of a garment which is joined to a lower, or skirt portion by a suitable waist band 3.

40 The present invention seeks to provide a construction which will be more effective than anything heretofore used to preclude the seam of the garment from tearing under the arm, as it is at this place most garments are worn out. Especially is this a fact with 45 garments worn by ladies with tendency toward stoutness.

In overcoming this difficulty I have provided the sleeves 9 of the garment with reinforcing sleeves 5, comprising single strips of material as shown in Fig. 4, which are made to fit within the outer sleeves and extend from the ends thereof up over the shoulders and thence downwardly and connect with the waist band at the sides of the front and back.

The adjacent edges of the sleeve reinforcing strips and also the edges of the fabric forming the garment sleeves and waist are all secured together by a seam 2 in what 60 is known as a French seam, and the same extends from the end of the under side of the sleeve up under the arm and down the side of the garment to the waist band.

Particular attention is called to the construction of the seam; this is made by placing the edges of both the reinforcing member and outer garment which are to be joined, together with the outside of the fabric facing out and placing a row of stitching as at 10 adjacent the edge to fasten all the edges together, then turning the matched portions of the fabric back on opposite sides of the stitching, as at 11, and again stitching through all parts with parallel rows of 70 stitching 12 and 13 between which is placed a strip of tape 4, which extends from the outer end of the sleeve and connects with the waist band at 3. This provision doubly reinforces the seam so that when the arm is 80 lifted the strain will be directly applied to the tape rather than having the strain resisted by the stitching of the seam.

The two sleeves may be stitched together 85 across the shoulders but the inner sleeve member is preferably made to fit more closely than the outer so as to afford circulation between the members and to preclude the stays of the corset from piercing the 90 fabric of the outer garment.

Having thus described my invention what I claim as new and desire to protect by Letters Patent is:

1. In a garment of the character described, a reinforcing member consisting of 95 a single strip disposed within the garment reinforced thereby, and secured at its ends to the waist band of the garment at the side of the front and back; the strip extending over the shoulder, and having a sleeve forming portion extending within the garment sleeve and a seam securing the adjacent edges of the strip.

2. In a garment of the character described, a reinforcing member comprising 105 a single strip applied interiorly of the garment to extend over the shoulder and having its opposite ends secured to the waist band of the garment at the side of the front and back and having a sleeve forming portion extending within the garment sleeve; the adjacent edges of the reinforcing strip 110

being secured within the seam which likewise secures parts of the garment to which it is applied.

3. In a garment of the character described, a reinforcing member comprising a single strip applied interiorly of the garment to extend over the shoulder and having its opposite ends secured to the waist band of the garment at the side of the front and 10 back and having a sleeve forming portion extending within the garment sleeve; the adjacent edges of the reinforcing member and corresponding edges of the front and back parts of the outer garment all being 15 secured together by a seam comprising spaced rows of stitching and a reinforcing strip located within the seam, extending from the end of the sleeve to the waist band of the garment.
- 20 4. A garment waist having an outer and a short inner sleeve, said inner sleeve having wings extending from its shoulder section downwardly to the waist line, the outer end of the inner sleeve being stitched to the 25 outer sleeve, the meeting edges of the inner sleeve and of its downwardly extending wings being stitched together and to the

outer sleeve and waist by a seam which extends along the under side of the sleeve and then down to the waist.

30 5. A garment waist having an outer and a short inner sleeve, said inner sleeve having wings extending from its shoulder section downwardly to the waist line, the outer end of the inner sleeve being stitched to the outer sleeve, the meeting edges of the inner sleeve and of its downwardly extending wings being stitched together and to the outer sleeve and waist by a seam which extends along the under side of the sleeve and 35 then down to the waist and a reinforcing tape stitched into said seam.

40 6. A garment waist having an outer and a short inner sleeve, the inner sleeve having wings extending downward to the waist line, 45 and stitched to the waist body in such manner as to support the waist body and leave the shoulder part of the waist and outer sleeve loose over the shoulder, the outer end of the inner sleeve being stitched to the 50 outer sleeve.

Signed at Tacoma, Washington, this 21st day of March, 1919.

MARY M. GELLENBECK.
